US00D938378S

(12) **United States Design Patent** (10) **Patent No.:** **US D938,378 S**
Andresen (45) **Date of Patent:** ** *Dec. 14, 2021

(54) **CONTROLLER FOR VIDEOTELEPHONY DEVICE**

(71) Applicant: **NEATFRAME LIMITED**, Uxbridge (GB)

(72) Inventor: **Simen Andresen**, Fornebu (NO)

(73) Assignee: **Neatframe Limited**, Uxbridge (GB)

(*) Notice: This patent is subject to a terminal disclaimer.

(**) Term: **15 Years**

(21) Appl. No.: **29/728,783**

(22) Filed: **Mar. 20, 2020**

(30) **Foreign Application Priority Data**

Sep. 20, 2019 (EM) 006887436-0003

(57) **CLAIM**

The ornamental design for a controller for videotelephony device, as shown and described.

DESCRIPTION

FIG. 1 is a front elevation view of a controller for videotelephony device showing my new design;

FIG. 2 is a rear elevation view thereof;

FIG. 3 is a top plan view thereof;

FIG. 4 is a bottom plan view thereof;

FIG. 5 is a right side elevation view thereof;

FIG. 6 is a left side elevation view thereof; and,

FIG. 7 is a rear perspective view thereof.

The broken lines in the drawings illustrate portions of the controller for videotelephony device that form no part of the claimed design.

1 Claim, 7 Drawing Sheets
